(57) **CLAIM**

The ornamental design for a flexible conduit dispenser case as shown and described.

DESCRIPTION

FIG. 1 depicts a right perspective view of a flexible conduit dispenser case showing my new design;

FIG. 2 depicts a right elevational view thereof;

FIG. 3 depicts a left elevational view thereof;

FIG. 4 depicts a top plan view thereof;

FIG. 5 depicts a bottom plan view thereof;

FIG. 6 depicts a rear elevational view thereof; and,

FIG. 7 depicts a front elevational view thereof.

The broken lines in the drawings depict portions of the flexible conduit dispenser case that form no part of the claimed design.
